UNITED STATES PATENT OFFICE.

AMBROSE K. BRETELLE, OF CHICAGO, ILLINOIS, ASSIGNOR OF ONE-HALF TO CHARLES H. STEPHENS, OF CHICAGO, ILLINOIS.

GAS-BURNER.

1,129,546.

Specification of Letters Patent. Patented Feb. 23, 1915.

Application filed May 29, 1914. Serial No. 841,791.

To all whom it may concern:

Be it known that I, AMBROSE K. BRETELLE, a citizen of the United States, residing at Chicago, in the county of Cook and State of Illinois, have invented certain new and useful Improvements in Gas-Burners, of which the following is a specification.

This invention relates to attachments for gas burners designed to save fuel and to intensify the heat produced by the flame, and with this object in view, the invention consists in a device to be hereinafter described in detail and claimed.

In order that the invention may be better understood, reference is had to the accompanying drawing, in which—

Figure 1 is a perspective view of the device, and Fig. 2 is a vertical section thereof in position over the burner of a gas stove.

As shown in the drawing, the device consists of a dome-shaped cap 5 in the top of which, at the center thereof, is an opening 6. The top and the side of the cap are also provided with small perforations 7 and

25 7^a, respectively, and at the junction of said parts is a circular series of slots 8. The diameter of the cap, at the base thereof, is such that it may be placed over the burner 9 of an ordinary gas stove, as shown in Fig.

30 2. The device can be readily applied to any burner that can be covered by the cap and no alteration in the structure of the burner is necessary.

In operation, when the gas is ignited, a rush of air is induced through the perforations 7 and 7^a, which tends to draw air and

gas through the burner. This mixture passes through the cap 5 and striking the bottom of the utensil mounted over the

40 burner, burns with a solid blue flame. The heat created by the cap produces a suction

from the under side as well as from the side of the burner and causes air to rush under the cap, thereby atomizing the gas and intensifying the heat to a considerable degree. A perfect mixture of gas and air results whereby a greater degree of heat from a smaller quantity of gas is produced. The air supply increases as the flow of gas increases, and there is no waste of gas from imperfect combustion. The action of the cap is similar to a stack or chimney. The amount of air passing through the air pipe of the burner is automatically regulated by the flow of gas and by the suction produced by the heat rising under the cap. The slots 8 equalize and reduce the size of the flame in the center opening 6, making the flame strike the surface to be heated with equal force. The perforations 7 and 7^a are contracted at their outer ends, which increases the suction.

The number of slots and perforations will depend on the size of the cap, the latter being made in various sizes to suit different sized burners.

I claim:

An attachment for gas burners comprising a cap open at the base to seat over the burner, the top of the cap being flat, and its side being flared toward the base, said top of the cap having a central opening, and the side of the cap having apertures, said cap also having slots at the junction of the top and side, and perforations in the top surface rounding the central opening.

In testimony whereof I affix my signature in presence of two witnesses.

AMBROSE K. BRETELLE.
